UNITED STATES PATENT OFFICE

WILLIAM DUBILIER, OF NEW ROCHELLE, NEW YORK, ASSIGNOR TO DUBILIER CONDENSER CORPORATION, OF NEW YORK, N. Y., A CORPORATION OF DELAWARE

MEANS FOR DIMMING LAMPS

Application filed February 1, 1926. Serial No. 85,362.

This invention relates to improvements in means for dimming lamps, particularly incandescent electric lamps.

An object of the invention is to provide a simple and inexpensive device which can be used in connection with practically any standard incandescent lamp and the socket in which such a lamp is usually inserted to connect it in circuit with the source of electrical power; and which will operate with practically no heat or loss of electrical energy, such as is usually incurred when dimming devices comprising resistances in circuit with the filaments of incandescent lamps are used.

A further object of the invention is to provide means for dimming an incandescent electric lamp which comprises very few parts and is of such design that anyone can operate it, and which presents very little likelihood of being deranged or getting out of order in practice.

Other objects and advantages of this invention will fully appear from the following description, taken with the accompanying drawings which illustrate one or more embodiments of the best forms of my invention now known to me; but the disclosure is, of course, explanatory only, and I may vary the arrangement of parts and details of construction to the full extent indicated by the nature and scope of the invention as set forth in the general terms of the appended claims.

On the drawings:

Figure 1 is a view of an electric lamp attached to means for dimming same according to my invention, said means being shown in section.

Figure 2 is a side view partly in section of another form of my invention.

Figure 3 is a diagram of the circuits used in the structure shown in Figure 2.

Figure 4 is a section of the line 4—4 of Figure 3; and

Figure 5 is a side view of another form of dimming means according to my invention.

The same numerals identify the same parts throughout.

Referring first to Figure 1, I show in this form of my invention an incandescent lamp comprising a bulb 1 containing a filament 2. When an electric current traverses this filament, it burns brightly and becomes a source of illumination in the usual way. One end of the filament is connected to the usual threaded sleeve 3 on the neck of the lamp, while the opposite end is united to a terminal 4 at the end of this neck. At 5 I indicate a condenser within a plug 6 of insulation or other material, the outside of which is covered by a threaded sleeve 7 of some conductive material, the same as the threaded sleeve or bushing 3. One end of this plug 6 carries an outside terminal 8 to which one pole of the condenser 5 is joined and the opposite end of this plug carries a similar terminal 9 to which the opposite pole of the condenser is connected. At 10 is a sleeve of insulation having a bore therethrough, open at both ends and lined with a metallic threaded sleeve 11. The plug 6 is screwed into one end of the sleeve or coupling 10 and the lamp 3 in the opposite end. When the terminal 4 makes contact with the terminal 9, the filament is in circuit with the condenser, and when the end of the plug 6 carrying the terminal 8 is screwed into the ordinary lamp socket, the filament 2 of the lamp can be put in circuit with the source of electric power through the central terminal of the socket which will make contact with the terminal 8 and through the threaded metallic sleeve 7, which will engage the usual threaded lining of the lamp socket. As this lining of the lamp socket is connected to one side of the power circuit, and the central terminal of the lamp socket to the other side of the power circuit, the lamp 1 will receive current in the same way as when an ordinary incandescent lamp is screwed into such socket directly, without the intervention of any such member as the plug 90

6 or coupling sleeve 10. My invention is, of course, intended for employment on circuits for alternating current, and by giving the condenser 5 the proper capacity and design, 5 only a small quantity of current reaches the filament 2, and when the lamp is utilized in connection with such a condenser, it gives but a small amount of illumination and uses but a small part of the total current. At the 10 same time, there is practically no waste or loss, and the invention can be readily practiced, because all that is necessary is to screw the lamp bulb 1 into one end of the coupling 10 and the condenser containing plug 6 into the usual socket. When the dimming means 15 is not desired, the plug 6 and the sleeve 10 can be discontinued and the lamp 1 can be screwed into the socket directly to make the lamp give the full illumination for which it 20 is constructed. This device works very well on alternating circuits and is much simpler than the ordinary form of dimming device involving resistance coils, is more durable and much less likely to become damaged or 25 get out of order. Obviously, the plug 6 and the coupling 10 can be made in one piece and permanently secured to each other if desired.

This means for dimming the filament 2 of the lamp, besides being not only simpler and 30 less expensive as well as less cumbersome and smaller than a resistance coil or some other appliance, has the additional advantage that it will operate without heating, and I thus obtain the desired result without really adding anything to the lamp or the circuit in 35 which it works, because the condenser 5 is really more of a gap in the power circuit leading to the lamp than any extra apparatus inserted therein.

40 In Figures 2, 3, and 4 I show another embodiment of my invention, which comprises a casing 12 having adjacent one extremity a threaded metallic sleeve 13 which extends all the way from said end up to a collar 14. In 45 the opposite extremity is a socket or recess 15 containing a threaded metallic lining 16 united to the sleeve 13 by conductor 17, which may be embedded in the insulating material of which the body of the casing 12 is made. 50 In the one end adjacent the sleeve 13 is a terminal 18 and in the socket or recess 15 is another terminal 19. Inside of the casing 12 is a condenser 20, one terminal 21 of which is joined to a conductor 22 which passes 55 through the adjacent end portion of the casing and connects with the terminal 18, and the point of junction of the conductors 21 and 22 is united to a conductor 23 which leads to a contact 24. The opposite terminal of the 60 condenser 20 is connected by a wire or conductor 25 to another contact 26, and adjacent the contacts 24 and 26 is a third isolated contact 27. These three contacts are preferably 65 located on the outside of the casing 12 in a housing or cover 28, and in this housing or

cover is a switch 29 on a shaft 30 which carries, outside of the cover, an operating knob or the like 31, by turning which the switch 29 can be moved. The switch is permanently in contact with a suitable conductor such as 70 a brush 32 which is connected to the terminal 19. By means of this arrangement, as shown practically in Figures 2, 3, and 4, if one turns the knob 31, it can make the switch 29 engage the contact 24, the contact 26, or the contact 75 27. When lamp 1 is screwed into the recess 15, one end of the filament attached to the threaded sleeve or bushing 3 is put in circuit with the sleeve 13 and the other end of the filament united to the terminal 4 engages the 80 terminal 19 and is put in circuit with the terminal 18. If the switch rests upon the contact 27, both the lamp and the condenser are out of circuit. If the switch is turned to engage the contact 26, the condenser is in circuit and the lamp is dimmed. By moving the switch further to engage the contact 24, the condenser is cut out and the lamp is caused 85 to give its maximum illumination.

In Figure 5 I show a form of my invention 90 very similar to Figure 2, except that the lamp is controlled by means of a pull chain. In this form the switch which controls the lamp and the condenser can be placed between the condenser 20 and the collar 14. Such a switch 95 is indicated diagrammatically at 34, and the pull chain is shown at 35, which enters the interior of the casing 33 by way of a funnel shaped bushing 36. I do not need to describe the construction of the switch 34 in 100 this application, as this switch works upon the principle of any three point snap switch with a suitable member attached to the chain 35 in the casing 33 and mounted so that it always tends to return to its original position. Such a member will engage the switch arm so 105 that when the chain 35 is pulled, it will at first connect in the condenser 21 in circuit with the lamp and then on the next pull, the condenser will be cut out and the filament 110 connected in the power circuit so that it will give its full illumination. Then on the next pull of the chain 35, the lamp will be extinguished so that when it is again desired to 115 use the lamp, the first pull of the chain will once more connect in the condenser and lamp together.

To use the two forms of the invention shown in Figures 2, 3, 4, and 5, one need only 120 screw the sleeve 13 into an ordinary lamp socket and the lamp 1 into the recess 15.

My invention is not only cheaper to make than dimming devices of the kind which include resistance coils, but also it is simpler, easier to operate, less liable to become impaired, and it further eliminates loss and heating of the entire apparatus.

The coupling sleeve 10 shown in Figure 1 is, of course, preferably made of insulation, 125 and it will be seen that the complete fitting 130

shown in Figure 1, as well as those shown in Figures 2 and 5 necessarily comprises a connector plug at one end, same as the end of the lamp which bears the threaded conductor sleeve 3, while the opposite end constitutes a socket just like the ordinary socket which is used in electric fixtures so that the lamps can be attached thereto by screwing them in place, and detached by screwing them out. Hence, my invention can be employed with the apparatus now commonly used in the wiring circuits of dwellings and other structures.

My invention will dim a lamp very effectually and yet not enough current will be consumed to appear on the electric meter in the circuit of the lamp.

Having described my invention, what I believe to be new and desire to secure and protect by Letters Patent of the United States is:—

1. An attachment plug comprising a tubular body of insulating material, input terminals at one end thereof for connecting the plug to a source of current, output terminals near the other end thereof for connecting a work circuit to the plug, a conductor disposed in the wall of said body electrically connecting one of the input terminals to one of the output terminals, and a condenser disposed within said tubular body and adapted to be connected between another of the input terminals and another of the output terminals for limiting the current supplied to the work circuit.

2. An attachment plug as defined by claim 1 and a switch secured to the wall of said body, said switch having terminals connected respectively to the last mentioned input and output terminals and a terminal of said condenser.

3. An attachment plug adapted to be connected between an electric outlet and an electric power consuming device, comprising a hollow body of insulating material having a flat exterior surface portion, input terminals secured to said body and adapted to connect the plug to said outlet, output terminals secured to said body for connecting said power consuming device to the plug, a condenser disposed within said hollow body, a switch mounted on the flat portion of said body and adapted to selectively connect one of said input terminals to one of said output terminals directly or in series with said condenser, and a conductor carried by the wall of said body electrically connecting another of said input terminals to another of said output terminals.

4. An electric lamp dimming device comprising a tubular body of insulating material, means at one end of said body for connecting the device with a lamp socket, means at the opposite end of said body for receiving the base of an electric lamp, each of said means comprising a sleeve terminal and

a central pin terminal said terminals being axially aligned with said tubular body, a conductor carried by the wall of said body electrically connecting said sleeve terminals and a reactance disposed within said body directly between said pin terminals and having one terminal thereof connected to one of said pin terminals and the other terminal thereof adapted to be connected to the other pin terminal.

In testimony whereof I affix my signature.

WILLIAM DUBILIER.
